UNITED STATES PATENT OFFICE.

WILLIAM KLOCKE, OF BROOKLYN, NEW YORK, ASSIGNOR TO E. W. BLISS COMPANY, OF BROOKLYN, NEW YORK, A CORPORATION OF WEST VIRGINIA.

DRAWING-PRESS.

1,130,176.

Specification of Letters Patent. Patented Mar. 2, 1915.

Application filed September 2, 1914. Serial No. 859,789.

To all whom it may concern:

Be it known that I, WILLIAM KLOCKE, a citizen of the United States, residing in Brooklyn, county of Kings, State of New York, have invented certain new and useful Improvements in Drawing-Presses, of which the following is a specification.

My invention relates to drawing presses and has for its object to provide means whereby a double-action press may quickly and simply be converted into a single-action press. By double-action presses, I mean a press wherein the work is supported upon a bed and is held in place by a reciprocating blank-holder while the operating member, frequently called a punch, is brought into operative position usually inside the blank-holder.

It is frequently highly desirable in shops employing double-action presses, to have a single-action press which shall have the capacity for work of a larger size usually possessed by a double action press. The large expense attendant upon the manufacture of heavy presses of this character frequently prevents the shop from obtaining such additional press. It will consequently be perceived that great economy would be obtained if means were provided to simply and efficiently transform a double-action press into a single-action press.

My invention has for its object to accomplish this purpose, and it consists in devices whereby the blank-holder and punch may be locked together when it is desired that the press shall act as a single-action press, and further, to provide means for disconnecting one of said presses from its operating devices so that the said part which then acts as a single die shall be under the sole control of the remaining operating device.

A desirable form in which my invention may be made is illustrated in the accompanying drawings, wherein—

Figure 1 is an elevation of a press embodying my invention; Fig. 2 is a vertical section on the line 2—2 looking in the direction of the arrow; Fig. 3 is a similar view illustrating the locking devices in place and the blank-holder operating devices disconnected; Fig. 4 is a detail longitudinal section of the adjustable locking device for connecting the blank-holder and punch; and Fig. 5 is a detail view of the device for disconnecting the blank-holder operating links.

My invention is applicable to double-action presses generally, and is illustrated particularly in connection with a press of the type illustrated in my Patent No. 955,173, dated April 19, 1910, which is a double-crank double-acting press.

In the press illustrated the blank-holder or the carrier, upon the lower face of which the blank-holder is mounted, is indicated at A. For convenience of reference the said part will be hereinafter referred to as a blank-holder. Within this blank-holder is situated the plunger B, upon the lower face of which the upper die or punch is mounted.

To facilitate the understanding of my invention as applied to the particular machine illustrated, I will give a brief description thereof.

The bed C carries the lower die upon the face of which the material is clamped and worked. The blank-holder A is guided upon the side frames E E¹ of the machine by guides D, and the plunger B is guided within the blank-holder. The plunger is driven from links F F¹, which may be adjusted in length as desired in any suitable manner, as shown in my said patent. The links are connected at their upper ends to cranks H H¹ upon the plunger actuating shaft J, which has end bearings in the end frames E E¹, and an intermediate bearing K depending from a web L extending across at the top between the side frames. The shaft J is provided at its opposite ends with gears M M¹, which are driven from pinions N N¹ on opposite ends of a cross-shaft O, which cross-shaft carries a gear P on its left hand end by which it is driven from a pinion Q mounted on a shaft R extending across the rear of the machine parallel with the shaft O, and having at its right hand end a gear S which is driven from a pinion T on the driving-shaft U which carries the usual fast-and-loose pulleys V W at its left hand end. The movement of the blank-

holder is effected through links a² a³, and a pair of similar links, only one of which, a¹ is shown in the drawings, said links being connected to the four corners of the blank-holder A, which are operated with a sort of toggle action by cranks e e¹ upon rock-shaft e overhead. The front rock-shaft e operates the links a² a³ and the rear rock-shaft e¹ actuates the opposite links, one of which is shown at a¹. The driving and

the driven connections are substantially the same for these two rock-shafts. The rock-shaft c is driven by means of arms $f f^1$ at its opposite ends and close to the said frames of the machine, these arms being connected by links $g g^1$ to slides $h h^1$ which reciprocate vertically. As the slides $h h^1$ approach their upper ends, the links $g g^1$ approach a horizontal position. When the links $g g^1$ are approximately horizontal and the arms $f f^1$ and cranks $e e^1$ are approximately vertical, the blank-holder is pressed to its final position. The slides $h h^1$ are driven from the plunger-actuating shaft or gears, and are located at opposite ends of the shaft. These slides are guided at their upper and lower ends by guideways $j j$ embraced by flanges $l m$ respectively at the upper and lower ends of the slides, and formed on the upper projecting rib Y , and a similar lower projecting rib n . The slides $h h^1$ are located between the gears $M M^1$ and the corresponding side frames and are driven therefrom by means of links o connected at their upper ends to crank pins p upon the outer faces of the gears, and at their lower ends to pins q upon bosses r constituting extensions of the lower portions of the slides. Various details of construction of the said press are not described herein as they are not necessary to an understanding of my invention—they will be found in my aforesaid patent.

According to my present invention, means are provided whereby my double-crank double-acting press is converted into a double-crank, single-acting press. For this purpose it is necessary that the blank-holder and plunger which carries the punch should act as a unit and form a single tool for any desired operation to be performed upon the machine. I accomplish this by providing means for locking the said parts together. Such means may be any convenient way of accomplishing this purpose, the most desirable form now known to me being the employment of a tongue G which is illustrated as carried upon the blank-holder and extending horizontally in line therewith. It is adjustable in position and may be moved forward to engage and lock the plunger. For this purpose the plunger is illustrated as being provided with a groove G^1 of a size to snugly receive the tongue G . Means are provided to adjust the tongue to and from locking position, and such means, as illustrated, comprise a series of screws $g g^1$. The screws g pass freely through threaded openings in bosses g^2 projecting upwardly from the tongue and are threaded into a part g^3 of the blank-holder, which is relatively fixed. The tongue may be drawn forward to locking position by turning the screws g , of which three are illustrated, so that the head of the said screw will draw

the tongue forward into the groove in the plunger. The bolt g may have the head fixed on it if desired, or the same may take the form of a nut g^4 , by the turning of which on the threaded bolt g the tongue g^3 may be drawn to locking position. For withdrawing the tongue from locking position the screws g^1 are provided. These are threaded into bosses g^2 and abut against the relatively fixed part g^3 of the blank-holder, thereby as the said screws are turned forward in their supports they withdraw the tongue from locking position. Bolts g' are unscrewed as the tongue is forced to locking position.

In order that the blank-holder and plunger may operate as a single tool it is necessary that one or the other of them should have its operating devices disconnected as these do not cause the said parts to operate coincidentally. I prefer to disconnect the blank-holder from its operating devices and accordingly I have shown means for accomplishing this purpose. In view of the fact that the press with which my invention is illustrated is a double crank press, it is necessary that both sets of operating devices should be disconnected simultaneously, and this may well be accomplished by withdrawing the pivots $a^4 a^5$ upon which the links $a a^2$ are mounted. To accomplish this I have provided a turn-buckle X , which comprises an internally threaded sleeve x , which receives the threaded ends of the pivots $a^4 a^5$, and being turned by the handle a^6 withdraws the said pivots from the links and permits the same to drop out, as illustrated in Fig. 3, where I have provided shoulders a' to support them. There being two pairs of links, the turn-buckle and removable pivots will be provided for each pair so that all of the operating devices for operating the blank-holder may be disconnected when desired. The conversion of the double-acting press to a single-acting press does not affect the balance of the parts in view of the fact that the heavy slides $h h^1$ will still be connected to the gears $M M^1$ and will balance the weight of the associated plunger and blank-holder, as heretofore.

The double-acting press herein illustrated, when converted by means of my invention as herein described to a single-acting press will be found as efficient and useful for this purpose as though it had been constructed as a single-acting press, and by this means I am enabled to provide two presses for substantially the price of one.

Although I have described with great particularity the construction of press to which my invention is applied, it is understood that its utility is not limited to the type of press employed, as it might equally well be employed with other double-acting

presses; nor is my invention limited to the particular manner which I have illustrated of accomplishing the purpose desired. Although these are the best ways now known to me of carrying my invention into effect, it will be apparent that other methods of accomplishing this object may be devised, and my invention is broad enough to cover such other constructions within the limits 10 of the appended claims.

What I claim is:—

1. In a double-acting press having a blank-holder and a plunger, means for converting the same into a single-acting press, comprising a lock for locking together the blank-holder and plunger, and means for disconnecting one of said parts from its operating mechanism.

2. In a double-acting press having a blank-holder and a plunger, means for converting the same into a single-acting press, comprising a lock for locking together the blank-holder and plunger, and means for disconnecting the blank-holder from its operating mechanism.

3. In a double acting press having a blank-holder and a plunger, means for converting the same into a single-acting press, comprising a lock in the blank-holder for locking it to the plunger, and means for disconnecting one of said parts from its operating mechanism.

4. In a double-acting press having a blank-holder and a plunger, means for converting the same into a single-acting press, comprising a lock in the blank-holder for locking it to the plunger, and means for disconnecting the blank-holder from its operating mechanism.

40 5. In a double-acting press having a blank-holder and a plunger, means for converting the same into a single-acting press, comprising an adjustable tongue on the blank-holder adapted to enter a corresponding groove in the plunger and lock the blank-holder and plunger together, means for adjusting the tongue into and out of locking position, and means for disconnecting one of said parts from its operating mechanism.

50 6. In a double-acting press having a blank-holder and a plunger, means for converting the same into a single-acting press, comprising an adjustable tongue on the blank-holder adapted to enter a corresponding groove in the plunger and lock the blank-holder and plunger together, a headed screw threaded into said blank-holder and having its head engaging the tongue for moving the tongue into locking position, a screw threaded into said tongue abutting against said blank-holder for moving said tongue

out of locking position, and means for disconnecting one of said parts from its operating mechanisms.

65

7. In a double-acting press having a blank-holder and a plunger and operating devices therefor including a pivoted link, an adjustable lock for locking together the blank-holder and plunger, and means for disconnecting one of said parts from its operating devices comprising a removable pivot for said link.

8. In a double-acting press having a blank-holder and a plunger and operating devices therefor, said devices including a pivoted link as part of the devices for operating said blank-holder, an adjustable lock for locking together the blank-holder and plunger, and means for disconnecting said operating devices comprising a removable pivot for said link.

9. In a double-acting press having a blank-holder and a plunger and operating devices therefor, said devices including a pair of aligned pivoted links as part of the devices for operating said blank-holder, an adjustable lock for locking together the blank-holder and plunger, and means for disconnecting said operating devices comprising removable pivots for said links and a turn-buckle connected to said pivots for withdrawing or replacing the same simultaneously.

90 10. In a double-acting press having a blank holder and a plunger and means for converting the same into a single-acting press, comprising locking devices for causing the blank holder and plunger to operate in unison, an operating shaft for one of the parts, operating connections between said shaft and said part, and means for disconnecting said operating connections whereby the said blank holder and plunger are caused to operate as a single part without disturbing the balance of the machine.

105 11. In a double-acting press having a blank holder and a plunger, means for converting the same into a single-acting press comprising locking devices for causing said blank holder and plunger to operate in unison, operating devices including an additional link for operating one of said parts, means for disconnecting said operating devices, and a support in one of said moving parts for said link.

In witness whereof, I have hereunto signed my name in the presence of two subscribing witnesses.

WILLIAM KLOCKE.
